W. SCHMIDT,

MEANS FOR COOLING THE PISTONS OF INTERNAL COMBUSTION ENGINES.

APPLICATION FILED JAN. 18, 1916.

1,344,090.

Patented June 22, 1920.

WILHELM SCHMIDT, Inventor

O. V. Kiehl ATTORNEY.

UNITED STATES PATENT OFFICE.

WILHELM SCHMIDT, OF CASSEL-WILHELMSHÖHE, GERMANY, ASSIGNOR, BY MESNE ASSIGNMENTS, TO LOCOMOTIVE SUPERHEATER COMPANY, A CORPORATION OF DELAWARE.

MEANS FOR COOLING THE PISTONS OF INTERNAL-COMBUSTION ENGINES.

1,344,090.

Specification of Letters Patent. Patented June 22, 1920.

Application filed January 18, 1916. Serial No. 72,741.

To all whom it may concern:

Be it known that I, WILHELM SCHMIDT, a subject of the German Emperor, King of Prussia, residing at Cassel-Wilhelmshöhe, 5 Germany, have invented a new and useful Improvement in Means for Cooling the Pistons of Internal-Combustion Engines, of which the following is a specification.

My invention relates to internal combustion engines, particularly to such engines as 10 have means for cooling the piston and associated parts, and has, for an object, to provide a novel means, free from certain difficulties hitherto met with, for accomplishing 15 such cooling.

My invention is most usefully embodied in that type of internal combustion engine 20 which is operated in combination with a steam engine, preferably of the multi-expansion type.

In combustion engines the working piston and the cylinder walls are directly exposed to the excessively high temperatures of combustion and, therefore, themselves tend to assume 25 a very high temperature. A cooling of the cylinder walls and, particularly, of the piston proper is, therefore, greatly to be desired. So far as concerns the piston, however, structural and operative difficulties together 30 with the entailed loss of heat has caused such cooling to be very little practised. Should the dimensions of the combustion cylinder, however, exceed a certain limit, which limit is attained earlier in the 35 case of two cycle engines than in the case of four cycle engines, this piston cooling becomes absolutely necessary.

Hitherto cooling of the piston has been principally effected by means of liquids, 40 water or oil, for example; air has also been proposed as a substitute for liquids. In cooling with liquids the constructions proposed have involved considerable complexity, particularly as regards the arrangement 45 of the inlet and outlet conduits, which has affected the certainty of operation of the engine; furthermore, liquid weight in the piston has necessarily increased the mass of the moving parts and hence disturbed the 50 smooth running of the engine. In cooling with air, on the other hand, it has been found impossible to sufficiently reduce the temperature of the piston.

Furthermore, whether liquid cooling or

air cooling has been practised, in either case 55 there has been no effective utilization of the abstracted heat.

By means of my invention herein described the above referred to disadvantages are avoided and an effective cooling of the 60 piston provided, together with an efficient utilization of the abstracted heat.

Briefly described, my invention comprises a current or currents of exhaust steam as a 65 cooling medium, said steam being led through one or more hollow spaces of the piston. As the exhaust steam thus flows over the parts heat is abstracted from and associated parts cooled; simultaneously the abstracted heat dries and superheats the 70 steam which may then be utilized in any desired manner, or the steam may be exhausted to the atmosphere.

My means will be found especially applicable to combined combustion and steam 75 engines, particularly when the steam engine is of the multi-expansion type. In such combination engines the exhaust steam may be taken from the high pressure cylinder, or from one of the low pressure cylinders, 80 through the combustion engine piston, from which it abstracts heat which dries and superheats the steam; the steam is then carried to a steam cylinder or cylinders of lower pressure. Thus there is solved the difficult 85 problem referred to of drying and superheating steam which has already performed work and of utilizing said steam so as to secure a return from the heat which has been used to perform such drying and super- 90 heating.

In carrying out my invention I prefer to employ a combination internal combustion and steam engine which employs a common cylinder having a combustion space at one 95 end and a steam space at the other. This affords the advantage that the exhaust steam may be led through the piston by the shortest possible path.

Such a combination engine is shown in 100 the accompanying drawing which represents a central longitudinal section through the common cylinder of a combined two cycle combustion engine and a steam engine having slotted outlets.

Referring to the drawing a cylinder of uniform diameter has a steam space A at one 105 end and a combustion space B at the other

end. A combined steam and combustion piston is adapted to move in this cylinder the end D closing the combustion space and the other end closing the steam space. The piston is made hollow with peripheral slots *c* opening therefrom near its steam end and other similar slots *e*, also opening therefrom but separated from slots *c* by a partition wall formed as a tube C which tapers toward and whose open end terminates near the inner surface of the combustion end D.

Other peripheral slots *a* are also provided at the very end of the piston which slots open into the steam space A.

15 An internal annular recess *b*, into which piston slots *a* and *c* are adapted to simultaneously open at the close of the steam expansion period, is provided.

An annular channel *h*, surrounds a similar channel *i* into which the exhaust combustion gases are discharged, the two channels having a common separating wall. The inner wall of each of these channels constitutes part of the cylinder wall and in these inner walls are provided inlet openings *f*, for channel *h*, and inlet openings *k*, for channel *i*. The two channels are also provided with outlet openings *g* and *m* respectively. The outlet *m* is connected by means of pipe *n* to the valve chest of the lower pressure steam cylinder *p*. This cylinder, its valve gear, etc., may be of any suitable construction.

The operation of my invention is as follows: In the position shown in the drawing, the steam expansion period being over, both slots *a* and *c* open into recess *b*. The exhaust steam, therefore, streams through these slots, by way of recess *b*, and up through the tube C against the inner surface of piston combustion end D. Here, it reverses direction and, by reason of the eddying thereby brought about, brings about an intensive cooling of the combustion end of the piston. The steam then passes downwardly over the inner peripheral wall of the piston, cooling it as it goes, and leaves the piston by way of slots *e* and *f*, now in coincidence, channel *h* and outlet *g*.

50 As the exhaust steam passes through channel *h* it abstracts heat which has been given to the partition wall common to channels *h* and *i* by the exhaust combustion gases previously discharged through inlets *k* and channel *i* after the piston has made its combustion power stroke. After being so heated as indicated the steam is carried by pipe *n* to the low pressure cylinder *p*, there to perform additional work in the usual way.

In the construction of my invention the steam working space, from which the exhaust steam is to be taken for cooling purposes, may be determined, according to the conditions present at the time, either as a single working stage, or as a high pressure or as an intermediate stage. In all such cases it is advisable to determine the exhaust pressure of the combustion gases at something higher than one atmosphere absolute as, in this way, any carrying of such gases or of oil residues back into the steam space is avoided.

The structure illustrated and described may be varied in details within the spirit of my invention. Thus it is not essential that there be but one combined combustion and steam piston and a common cylinder therefor and steam cylinder and piston may be separated from combustion cylinder and piston if desired. The exhaust inlets and outlets, also, may be valves of any desired type instead of simple slots as shown.

Having described my invention, I claim:

1. In apparatus of the class described, the combination of a multi-stage steam engine, an internal combustion engine, and means to carry the exhaust steam from an upper stage cylinder into contact with heated portions of the internal combustion engine and thereafter to a lower stage steam cylinder.

2. In apparatus of the class described, the combination of a multi-stage steam engine, an internal combustion engine, means to pass the exhaust steam from a steam cylinder of an upper stage into contact with the piston and exhaust passage walls of the combustion engine, whereby said combustion engine parts are cooled and the steam is superheated, and means to carry said steam to a steam cylinder of lower stage where it is permitted to expand.

3. In apparatus of the class described, the combination of a multi-stage steam engine, an internal combustion engine, and means to pass the exhaust steam from a steam cylinder of an upper stage to one of lower stage through a conduit comprising the hollow interior of the internal combustion engine piston.

In testimony whereof I have hereunto set my hand in the presence of two subscribing witnesses.

WILHELM SCHMIDT.
